GRADING MACHINE

James W. Johnston, Manchester, N. H., assignor
to North American Holding Corporation, Syra-
cuse, N. Y., a corporation of New York

Application April 16, 1935, Serial No. 16,573

4 Claims. (Cl. 271—51)

This invention relates to grading machines of the kind which grade died-out pieces of leather such as cut soles, taps and other blanks in accordance with their thickness as determined by a detecting or measuring device.

The principal object of the invention is to provide means to prevent a blank from swerving or being displaced edgewise from a straight path while it is being acted upon by the detecting or measuring device.

Although the invention is of broader application I will describe it, for the purpose of illustration, as applied to a grading machine of the type shown in the Cogswell Patents No. 1,686,487, dated October 2, 1928, and No. 1,820,010, dated August 25, 1931.

In the accompanying drawings,

Fig. 1 is a top plan view, partly in section and partly broken away, of a grading machine embodying the invention;

Fig. 2 is a longitudinal central section on the line 2—2 of Fig. 1;

Fig. 3 is an enlarged detail, partly in section and partly in elevation, illustrating one of the traction wheels hereinafter described; and

Fig. 4 is an elevation partly in section on line 4—4 of Fig. 2.

At the front of the machine is a magazine or hopper which holds the soles or other blanks S to be graded in a stack resting on a table or shelf 10. The blanks are automatically fed by the usual feeding mechanism one at a time from the bottom of the stack to the detecting and feeding rolls 15 and 16, by which the blanks are measured and propelled through the machine. The measuring and feeding rolls 15 and 16 are continuously driven in the directions indicated by the arrows in Fig. 2. As each blank passes between the rolls 15 and 16 the thickness of its thinnest part is detected and determined and the lower yielding roll 16 acts through the usual mechanism to set the pointer 17 relatively to the dial 18 of the usual indicator.

The blank is discharged from the rolls 15 and 16 upon the work-supporting bed 19 where it remains until it is removed by the operator from underneath the trip 14. Thereupon the trip 14 drops to the work bed 19 and sets in motion the feeding mechanism by which another blank is fed from the bottom of the stack of blanks S to the rolls 15 and 16.

For a more detailed description of the construction and operation of the machine, which has been generally outlined above, reference may be had to either of the two patents aforesaid.

Machines of this character are well known in the art and contain many parts which are not material to the present invention and which it is therefore not necessary to describe in explaining the present invention.

Each roll 15 and 16 comprises as usual two roll sections which are adjustably mounted, respectively, on shafts 11 and 12. The two sections of each roll are separated at the middle by an intervening space so that only the side marginal portions of the blanks are engaged by the rolls, since it is the usual practice to grade soles and the like according to the thickness of the thinnest measurement of the marginal areas, especially the marginal areas of the forepart of the sole. It is therefore important that the blank pass through the machine with the median line of its forepart parallel to its direction of movement and approximately midway between the two sections of each roll.

In the machines as heretofore constructed there is nothing to prevent the blanks, after leaving the magazine and while being propelled through the machine by the feeding and detecting rolls 15 and 16, from swerving edgewise, with the result that the median line of the blank sometimes swings laterally in one direction or the other instead of maintaining a straight path always parallel to the direction of movement of the blanks. Consequently it sometimes happens that the desired marginal areas of the blank are not correctly traversed by the roll sections and imperfect grading results. Such swerving movements may be occasioned by the action of the rolls 15 and 16 themselves, especially when the blank is not of uniform thickness from side to side, or they may be occasioned by the action of the usual feed slide by which the blanks are pushed out of the magazine.

To prevent this swerving or lateral edgewise displacement of the blank as it passes between the rolls 15 and 16 I have provided means associated with said rolls to exert positive and equal traction on both lateral margins of the blank thereby to insure the travel of the blank in a straight path without swerving as it is fed between the rolls. Preferably such means consists of a pair of spaced circumferential rows of prongs 20 which project beyond the surface of the rolls and which embed themselves sufficiently in the surface of the blank to exert positive and equal traction on both lateral margins of the blank and prevent the blank from swerving. As herein shown each circumferential row of prongs is formed on the periphery of a traction wheel 55

which is of ring-like form preferably composed of a plurality of removable sections. Two such sections 21 and 22, Fig. 3, are herein illustrated, but the wheel might consist of a different number of sections. Each section of the traction wheel is removably fastened to the inner end of its roll section by means of a screw 23 passing through a hole in the wheel or ring section and into a threaded bore in the end of the roll section.

As herein shown the pronged traction wheels are attached to the inner ends of the two sections of the lower roll 16. This is the preferred arrangement when leather blanks are to be passed through the machine with the flesh side or unfinished side down and the grain side or finished side up. Sometimes the blanks are passed through the machine with the finished side down and the unfinished side up. In that event the traction wheels may be secured to the inner ends of the two sections of the upper roll 15 by means of screws entering holes 24 (Fig. 2) provided for that purpose in the upper roll sections. In this way the defacing or marking of the finished side of the blanks by the prongs 20 may be avoided. To permit such interchangeability of the traction wheels between the upper and lower feed rolls 15 and 16, said rolls should be of the same diameter so that the prongs 20 will project the desired predetermined distance beyond the periphery or surface of the rolls; and the intervening spaces between the roll sections of the two rolls should be in register and should be identical in length so that no matter to which of the rolls the traction wheels are attached the intervening space between the roll sections of the opposite roll provides a circumferential recess opposite the projecting prongs of the traction wheels. The two shafts 11 and 12 are also preferably made of the same diameter so that the inner periphery of each ring or wheel section will fit against the shafts whether the traction wheels are applied to the upper or the lower roll.

I claim:

1. In a grading machine, a pair of measuring rolls each having two sections separated by an intervening circumferential recess registering with the corresponding recess in the companion roll, and a traction wheel secured at the inner end of each section of one of said rolls, each traction wheel having peripheral prongs projecting beyond the surface of the roll to which it is secured and into the intervening recess in the other roll.
2. In a grading machine, a pair of measuring rolls consisting of a driving roll and a driven roll, each roll having two sections separated by an intervening circumferential recess registering with the corresponding recess in the companion roll, and a traction wheel secured to the inner end of each section of said driven roll, each traction wheel having peripheral prongs projecting beyond the surface of the driven roll and into the circumferential recess in the driving roll.
3. In a grading machine, a pair of measuring rolls each having two sections separated by an intervening circumferential recess registering with the corresponding recess in the companion roll, and a traction wheel secured at the inner end of each section of one of said rolls, each traction wheel having peripheral prongs projecting beyond the surface of the roll to which it is secured and into the intervening recess in the other roll, and each traction wheel being made in a plurality of arcuate sections individually fastened to the end of the roll section.
4. In a grading machine, a pair of cooperating measuring rolls, one of said rolls having two sections separated by an intervening recess, and a pair of traction wheels secured to the other of said rolls intermediate its ends, said traction wheels having peripheral prongs projecting beyond the surface of the roll to which they are secured and into the intervening recess in the first mentioned roll.

JAMES W. JOHNSTON.
